UNITED STATES PATENT OFFICE.

HARRY A. BARNES, OF MILWAUKEE, WISCONSIN, ASSIGNOR TO THE PREMIER MANUFACTURING COMPANY, OF HARTFORD, CONNECTICUT.

DESIGN FOR AN UPPER MEMBER FOR FIFTH-WHEELS.

SPECIFICATION forming part of Design No. 33,169, dated September 4, 1900.

Application filed April 18, 1900. Serial No. 12,778. Term of patent 14 years.

To all whom it may concern:

Be it known that I, HARRY A. BARNES, a citizen of the United States, residing at Milwaukee, in the county of Milwaukee and State of Wisconsin, have invented and produced a new and original Design for an Upper Member for Fifth-Wheels, of which the following is a specification, reference being had to the accompanying drawings, forming a part thereof.

Figure 1 is a plan view of the upper member of a fifth-wheel, showing my new design. Fig. 2 is a front elevation thereof; and Fig. 3 is a sectional view taken on the line 3--3, Fig. 1.

As shown in the drawings, the leading or material features of my design consist of a substantially-circular plate A, formed on the upper side with a raised central cross-band B, slightly curved on the upper side and joining the upper face of said plate from end to end, as shown in Fig. 2. The plate A has two perforated ears a a, arranged diametrically opposite to each other on the front and

rear sides of said plate in a line substantially at right angles to the cross-band B, and two rearwardly-extending divergent arms C C, 25 joining said plate on the rear side next to the ends of the cross-band B. On the under side said plate is formed with a circular recess and with a central circular boss D, as shown in Fig. 3. The depending circular 30 flange E surrounding said recess is broken or partially cut away next to the perforated ears a a, as shown in Figs. 2 and 3.

Having thus described my invention, what I claim as new, and desire to secure by Letters 35 Patent, is—

The design for the upper member of a fifth-wheel as herein shown and described.

In witness whereof I hereto affix my signature in presence of two witnesses.

HARRY A. BARNES.
